GEORGE L. MEYER, OF MILWAUKEE, WISCONSIN.

GAS-ENGINE IGNITION.

1,349,846.

Specification of Letters Patent. Patented Aug. 17, 1918.

Application filed March 12, 1916. Serial No. 221,083.

To all whom it may concern:

Be it known that I, GEORGE L. MEYER, a citizen of the United States, and resident of Milwaukee, in the county of Milwaukee and State of Wisconsin, have invented new and useful Improvements in Gas-Engine Ignitions, of which the following is a description, reference being had to the accompanying drawings, which are a part of this specification.

This invention relates to gas engine ignition and has for its object to provide for the ignition of the compressed charge of explosive mixture by means of the explosion of a priming or detonating charge preferably of a more combustible fuel.

With the heavier and more slowly burning fuels such as kerosene, ignition by means of the spark plug is attended with difficulties such as the necessity for a high degree of compression or the presence of steam, and the slow burning action is not conducive to high speed operation owing to the sluggishness in the spread of flame throughout the charge. The present invention substitutes a detonator or primary explosion as a means for forcibly igniting the working charge throughout and accomplishing an increase in temperature and pressure of the working charge for insuring the development of its maximum efficiency of explosion early in the working stroke of the piston.

With the above and other objects in view, the invention consists in the gas engine ignition as herein claimed and all equivalents.

In the accompanying drawing I show a central sectional view of an exemplifying structure embodying the invention but it is to be understood that the invention is capable of embodiment in different forms.

In this drawing 10 indicates the gas engine cylinder with a piston 11 fitting therein having the usual connecting rod 12 connecting it with a crank shaft 13 journaled in a suitable casing 14. The cylinder is provided with an intake valve 15 and an exhaust valve 16, the former having connection with a carbureter 17 for the working fuel such as kerosene, and both being operated in the usual manner by cam actuated tappet rods 18 and rocker arms 19.

At the side of the cylinder and parallel therewith is an auxiliary or priming cylinder 20 in which fits a plunger 21 connected

by a connecting rod 22 with an eccentric 23 or a crank on the crank shaft 13. A communicating passageway 24 connecting the priming cylinder 20 with the working cylinder 10 is normally closed by means of a plunger 25 forming a yielding cylinder head for the priming cylinder. This plunger 25 is held forcibly in position to close said passageway by means of a heavy coil spring 26 confined between it and the screw plug 27. The spring is of such strength as to prevent the plunger 25 yielding to the pressure beneath it caused by the upward movement of the plunger 21 in compressing a primary charge but permitting the plunger 25 to yield to the increased pressure due to the explosion of the primary charge and so uncover the passageway 24 to vent the explosion into the combustion chamber of the working cylinder 10. The combustion chamber of the priming cylinder 20 is provided with an intake valve 28 which may be operated by a tappet rod or by suction to control the inflow of explosive mixture from a priming carbureter 29 for gasoline or other light fuel. The combustion chamber of the priming cylinder 20 is also provided with a spark plug 30. The functioning within the priming cylinder 20 is substantially the same as that in four-cycle gas engines, the force of explosion, however, instead of being utilized for ejecting the piston serving to move the yielding cylinder head 25 off of its seat to uncover the passageway 24 through which the exploding gases pass to the explosion chamber of the working cylinder. The forcible discharge of flaming burning gases from the priming cylinder into the working cylinder instantly ignites the entire compressed charge in the explosion chamber of the working cylinder so that all portions thereof are ignited at once instead of burning progressively. Furthermore, the pressure from the explosion in the priming cylinder increases the pressure of the charge in the working cylinder and this and the introduction of the burning gases raises the temperature of the charge in the working cylinder to produce conditions favorable to obtaining maximum efficiency even when a heavy fuel is used for producing the working charge.

A stem 31 on the yielding plunger 25 of the priming cylinder engages with the rocker arm 19 of the exhaust valve so that

when the exhaust valve is opened said plunger is lifted against the pressure of its spring to keep the passageway 24 open during the exhaust stroke of the pistons 11 and 21 whereby the exhaust gases from the priming cylinder are discharged through the open exhaust valve 16 along with the exhaust gas from the working cylinder.

While the invention has been described as pertaining to a four-cycle engine, it is equally suitable for use with a two-cycle engine and the priming explosion may be produced under conditions resembling those of a two-cycle engine or a four-cycle engine, as will be readily apparent to those skilled in the art. With the working cylinder operating on the two-cycle plan, two of the priming cylinders operating on the four-cycle plan may be employed so as to produce ignition for each working stroke of the piston in a working cylinder. The control of the timing of ignition in the working cylinder may be effected by the control of the timing of the explosion in the priming cylinder, and such timing adjustment may be made with compensating adjustment in the position of the cam or eccentric 23 with relation to the crank shaft so that ignition takes place in the same relative position of the plunger 21 of the priming cylinder, preferably its highest position, though the piston of the working cylinder may be in a different relative position either before reaching or after leaving its uppermost position according to whether it is desired to advance or retard ignition.

I desire it to be understood that this invention is not limited to any specific form or arrangement of parts except in so far as such limitations are specified in the claims.

The invention is not limited to the use of different fuels in the two cylinders, for the same fuel may be used and this may be a light fuel or a heavy fuel, and may be introduced through a carburetor or otherwise though the invention is particularly desirable for use with heavy fuel in the working cylinder and a light fuel in the priming cylinder.

What I claim as new and desire to secure by Letters Patent is:

1. In a gas engine, the combination of a priming explosion chamber having a valve controlled inlet distinct from the combustion chamber and a valve controlled outlet 55 communicating with the explosion chamber of the gas engine, and electrical ignition means for producing an explosion in said priming explosion chamber.

2. The combination, with a gas engine and its combustion chamber provided with means for supplying a charge of combustible mixture thereto, of a priming chamber having a valve controlled inlet distinct from said combustion chamber and a valve controlled 65 outlet in communication with the combustion

chamber, means for supplying a separate combustible mixture to the priming chamber, and electrical means for igniting the combustible mixture in the priming chamber whereby on the opening of its outlet valve 70 the flaming products of combustion will pass to the combustion chamber to cause ignition of the charge of combustible mixture therein.

3. The combination, with a gas engine and its combustion chamber, of a priming chamber having communication with the combustion chamber, a valve controlling such communication, means for supplying a charge of fuel to the combustion chamber, means for supplying another charge of fuel to the priming chamber, means for subjecting the priming chamber to compression when said valve is closed, and electrical means for igniting the compressed charge of fuel in the priming chamber to cause the flaming gases in said priming chamber to ignite the fuel in the combustion chamber on the establishment of communication between said chambers on the opening of the valve.

4. The combination, with a gas engine 90 and its combustion chamber, of a priming chamber having communication with the combustion chamber, means for supplying a charge of less volatile fuel to the combustion chamber, means for supplying a charge 95 of more volatile fuel to the priming chamber, means for compressing the charge of fuel within the priming chamber, electrical means for igniting the compressed charge of fuel in the priming chamber, and an intermittently movable valve controlling the passage of the flaming gases from the priming chamber to the combustion chamber.

5. The combination, with a gas engine and its combustion chamber, of a priming chamber for containing an explosive charge of fuel distinct from that of the combustion chamber and having communication with the combustion chamber, electrical means for igniting the fuel in the priming chamber, and valve means shutting off communication between said chambers but yielding under the pressure of the explosion in the priming chamber for establishing communication between the priming chamber and the 115 explosion chamber.

6. In a gas engine, the combination of a power cylinder and a priming cylinder having valve communication therewith, a piston working in the power cylinder, a plunger 120 working in the priming cylinder, means for supplying fuel to the power cylinder, means for separately supplying fuel to the priming cylinder, electrical means for igniting the fuel in the priming cylinder, and a 125 valve shutting off communication between said cylinders and yielding under the pressure of the explosion in the priming cylinder to establish communication between said cylinders.

7. In a gas engine, a power cylinder, a piston working therein, a valve-controlled fuel-introducing means therefor, an exhaust valve for the power cylinder, a priming cylinder, a plunger working therein, a valve-controlled fuel-introducing means for the priming cylinder, a spark plug for the priming cylinder, there being a passageway between the priming cylinder and the power cylinder, and a spring-seated valve closing said passageway and yielding under the force of explosion in the priming cylinder to open the passageway, said valve having connection with the exhaust valve and adapted to be opened therewith.

8. The method of producing ignition of a compressed charge of heavier fuel in the explosion chamber of a gas engine which consists in producing an explosion of an isolated charge of lighter fuel in a priming chamber and communicating the burning

gases of such explosion to the explosion chamber containing a less volatile fuel.

9. The combination, with a gas engine and its combustion chamber provided with an inlet and an exhaust valve, of a priming explosion chamber having a valve controlled inlet distinct from the combustion chamber and an outlet communicating with said combustion chamber, a valve controlling said outlet and opened by the pressure of explosion and on the opening of the exhaust valve for the combustion chamber, and means for producing an explosion in said priming explosion chamber. 35

In testimony whereof I affix my signature in presence of two witnesses.

GEORGE L. MEYER.
